United States Patent Office.

MARTIN LANDENBERGER, OF PHILADELPHIA, PENNSYLVANIA.

Design No. 4,358, dated September 20, 1870.

DESIGN FOR A SHAWL FABRIC.

The Schedule referred to in these Letters Patent and making part of the same

To all whom it may concern:

Be it known that I, MARTIN LANDENBERGER, of Philadelphia, in the county of Philadelphia and in the State of Pennsylvania, have invented certain new and useful Improvements in Fabric for Shawls; and do hereby declare that the following is a full, clear, and exact description thereof, reference being had to the accompanying drawing and to the letters of reference marked thereon making a part of this specification.

The nature of my invention consists in an improved design for a shawl fabric.

This design is fully represented in the accompanying drawing.

The stitch is made upon a shuttle-loom, and generally of two colors, as shown in the drawing; for instance, black and white, drab and blue, or any other colors desired.

Eight harnesses and forty-eight bars of chain are used in forming the design.

The accompanying drawing represents a view of the fabric as taken from the ordinary design-paper; and, while the fabric is incapable of specific description, it will be readily understood from the drawing by those skilled in the art.

The design forms a series of irregular-shaped oblique blocks and lines.

What I claim is—

The within-described design for shawl fabric, as shown.

In testimony that I claim the foregoing, I have hereunto set my hand this 25th day of August, 1870.

MARTIN LANDENBERGER.
